TROPHY BASE

Thomas F. Merle, Lincolnwood, Ill., assignor to Dodge, Inc., Chicago, Ill., a corporation of Illinois

Application May 14, 1957, Serial No. 46,160

Term of patent 14 years

(Cl. D29—23)

The dominant features of my design are shown in full lines in the drawings.

I claim:

The ornamental design for a trophy base, as shown and described.
